UNITED STATES PATENT OFFICE

2,241,966

MERCURY BOILER

Arthur R. Smith, Schenectady, N. Y., assignor to
General Electric Company, a corporation of
New York

Application August 17, 1938, Serial No. 225,435

4 Claims. (Cl. 122—235)

The present invention relates to mercury boilers comprising combustion and convection spaces with heating elements in which mercury is heated and partly evaporated. The circulation of mercury from a drum or like vessel through these heating elements may be effected either by natural flow or by pumping means. In the natural flow or circulation type boiler, mercury liquid is ordinarily conducted by downcomers external the furnace to the lower ends of heating tubes in which the mercury rises by thermo-syphon action caused by the formation of vapor in the up-tubes and by the difference in gravity between the relatively cold mercury contained in the down-tubes and the relatively hot mercury contained in the up-tubes. In forced circulation type boilers the mercury is circulated or forced through heating elements by means of a pump or pumps. The thermo-syphon type mercury boiler using ordinary mercury, without chemical treatment, has always been vulnerable and often not able to accept the heat of a modern furnace while the forced circulation boiler in which the mercury is forced downwardly and thereby capable of accepting more and more heat on its path through the fluid circuit, requires considerable pumping energy which reduces the over-all efficiency of such boiler.

The object of my invention is to provide an improved construction and arrangement of mercury boilers in which the principles of both the thermo-syphon and the forced circulation type boilers are combined to best advantage.

For a consideration of what I believe to be novel and my invention, attention is directed to the following description and the claims appended thereto in connection with the accompanying drawings.

In the drawings, Fig. 1 illustrates a mercury boiler embodying my invention, and Fig. 2 shows a modification of my invention.

The arrangement of Fig. 1 comprises walls 10 forming a combustion chamber 11, walls 12 forming a convection chamber 13 and walls 14 forming a bottom portion and connecting the lower end of the combustion chamber 11 with the lower end of the convection chamber 13. The walls are made of insulating and heat-resistant materials 15 covered outside by sheet metal 16. The bottom walls 14 and the walls 10 and 12 form sliding joints 17, 18 to permit relative movement between them during operation. The boiler walls are supported on a structure including vertical posts 19 and a plurality of horizontal beams 20. Fuel and air for combustion are sup-

plied to the combustion chamber through burners 21 connected to the ceiling of the combustion chamber and directed downwardly whereby during operation combustion in the chamber 11 progresses in downward direction and the combustion gases are conducted from the lower end of the chamber 11 to the lower end of the convection chamber 13 in which they rise upward. The walls 10 in the combustion chamber are lined in the present instance with substantially vertically arranged radiation heating tubes 22 and 23. The upper end portions of the tubes 22, 23 line the inclined ceiling in the combustion chamber and are connected to headers 24 and 25 respectively. Mercury liquid is forced into these headers 24, 25 by a mercury pump 26 which has an inlet conduit 27 connected to a vessel or drum 28 and discharge conduits 29 and 30 connected to the headers 24 and 25 respectively. The pump 26 is driven by an electric motor 31 and flexibly supported, in the present instance hung up on beams 32 by means including springs 33. The lower ends of the tubes 22 and 23 are connected to headers 34 and 35 respectively. The latter in turn are connected to the lower ends of rows of convection tubes 36 and 37 lining the walls in the convection chamber 13. The upper ends of at least some of these convection tubes are connected to the upper ends of banks of heating tubes 38 located in an upper, enlarged portion of the convection chamber at a level above the level of the drum 28. These banks of heating tubes 38 include a plurality of separate tubes having hairpin-shaped portions through which the flow of fluid takes place in a general downward direction. With reference to the downward flow these tubes may be designated inverted convection heating tubes or elements. The lower ends of the tubes 38 are connected to the drum 28. The drum 28 and the end portions of the tube 38 are located in a lateral extension of the convection chamber whereby the drum does not obstruct the flow of gases through the convection chamber and the end portions of the tubes 38 connected to the drum are protected from the direct heat in the convection chamber. The drum 28 includes a screen or baffle 39 for directing the mixture of liquid mercury discharged from the inverted convection heating tubes in downward direction towards a pool, thereby to prevent liquid particles from being carried away through a discharge conduit 40 connected to the drum 28. During starting the inverted convection tubes 38 being located above the level of the drum 28 are empty of mercury liquid. This reduces the

amount of mercury liquid necessary for operating the boiler and at the same time these tubes constitute considerable additional heating surface for mercury during normal operation.

During operation mercury liquid is forced by the action of the pump 26 into the upper ends of the down-tubes 22, 23 in the combustion chamber, whence it flows from the lower ends thereof through the up-tubes 37, 36 and finally through the inverted tubes 38 in the convection chamber into the drum 28. It will be noted that with this arrangement both up-tubes and down-tubes, that is, all tubes carrying mercury and forming a part of the fluid circuit, are located within the heating chamber. The down-tubes 22, 23 which receive mercury liquid directly from the drum are located in the combustion chamber and the up-tubes 36, 37 which receive heated mercury from the down-tubes as well as the inverted convection tubes 38 are located in the convection chamber. The tubes 22, 23 in the combustion chamber forming the first part of the circuit when viewed in the direction of flow from the drum are entirely filled with mercury liquid. These tubes accordingly can absorb a great amount of radiant heat energy in the combustion chamber. Circulation of the mercury in the fluid circuit is effected by both pumping and thermo-syphon action, the pumping action being caused by the pump 26 and the thermo-syphon action by the evaporation of a part of the mercury liquid in the convection tubes 36, 37 and the inverted convection tubes 38. The difference in gravity of the mercury contained in the tubes 22 and 36 causes upward flow of the mercury in the tubes 36 and, in addition, as just stated, the formation of vapor in the tubes 36 has a thermo-syphon effect, that is, it increases the velocity of flow through the convection tubes in the chamber 13 and consequently also the velocity of flow through the radiation tubes in the chamber 11. In order to obtain maximum circulation in an arrangement of this kind, it is important to prevent evaporation in the down-tubes 22, 23 because such evaporation would have an adverse effect on the circulation and might even cause reversed circulation. To this end it is important to provide means which permit evaporation only in the last part of the fluid circuit through which the mercury flows in upward direction. This last part of the fluid circuit in the present instance constitutes the tubes 36 and 37. Thus, evaporation of the mercury is to be permitted only after it has passed through the headers 34, 35 near the lower ends of the tubes 36, 37 respectively. An arrangement for controlling the evaporation by varying the speed of the circulating pump 26 is shown and will be described hereinafter in connection with Fig. 2.

The arrangement also includes means to permit relative expansion between the tubes and the adjacent walls of the boiler as well as to keep the tubes taut, thus preventing intermediate tube portions from moving away from the walls of the combustion and the convection chambers. To this end each tube has a plurality of spaced, U-shaped members 41 welded to its back and located in recess 42 in the wall. The members 41 are guided in openings of plates 43 which have portions embedded in the wall and fastened to the outer sheet metal cover 16. In this manner the tubes may move vertically relative to the wall. An arrangement of this kind is more fully described in an application of O. L. Wood, Serial No. 221,315, filed on July 26, 1933, and assigned

10 to the same assignee as the present application. Portions of the tubes 23 lining the bottom portion are secured to the latter by means of link 44, in fact the bottom wall 14 is at least partly supported on the tubes 23 in the combustion chamber and the tubes 37 in the convection chamber, thus keeping the tubes 23 and 37 taut. Likewise, a wall portion 45 connecting the adjacent walls of the combustion and convection chambers is supported on the tubes 22 and 36, thus keeping these tubes taut. In addition, the tubes 23, more specifically lower bent portions 46 thereof, are pulled downward and laterally outward by a mechanism including springs 47 and 48. Likewise, the lower portions of the convection tubes 37 near the header 35 are pulled downward and laterally outward away from the boiler by a mechanism including springs 50 and 51.

20 The arrangement of Fig. 2 comprises walls 55 forming a combustion chamber 56 and a convection chamber 57, the latter communicating at its lower end with the combustion chamber. Fuel is supplied to the combustion chamber by a burner 58 supported on the ceiling of the chamber. The walls of the combustion chamber are lined with up-tubes 59 and down-tubes 60 and 61 connected to an upper header 62 and to lower headers 63, 64 and 65 respectively, the down-tubes 60 lining a rear wall of the combustion chamber being connected to the lower header 64 and the down-tubes 61 lining a side wall being connected to the lower header 65. The convection chamber 57 contains up-tubes 66 connected at their lower ends to the headers 64 and 65 respectively and at their upper ends to a vessel or drum 67 having a deflector 68 and a discharge conduit 69.

25 Mercury liquid in this arrangement is forced from the drum 67 into the lower header 63 by means of a pump 70 having an inlet conduit 71 connected to the drum 67 and a discharge conduit 72 connected to the header 63. From the header 63 the mercury is forced through the up-tubes 59 into the upper header 62, whence the mercury flows through the down-tubes 60 and 61 into the lower headers 64 and 65 respectively and finally from said headers through the convection tubes 66 into the drum. The circulation of the mercury through the tubes in the combustion space, that is, through the up-tubes 59 and the down-tubes 60 and 61 is effected primarily by action of the pump 70, and the circulation through the convection tubes 66, the latter being connected in series with the radiation tubes in the combustion chamber, is effected primarily by thermo-syphon action. The tubes subjected to radiation in the combustion chamber are completely filled with mercury liquid. Evaporation takes place only after the liquid has reached the tubes 66 in the convection chamber. To this end, as pointed out above in connection with Fig. 1, means are provided to prevent evaporation in the tubes of the combustion chamber.

30 This mechanism comprises a temperature pressure differential responsive device including a temperature responsive device 73 and a pressure responsive device 74 having bellows connected to the ends of a floating lever 75, which latter is pivotally connected to a lever supported on a fulcrum 76 and having an arm carrying a switch 77. The switch 77 forms part of a relay circuit including a contact-making member 78 for short-circuiting a resistance 79. This resistance is connected into the circuit of a motor 80 for driving the pump 70. The pressure and tem-

perature responsive devices 13, 14 are connected to the lower header 65. An increase in temperature or a decrease in pressure effects closing of the switch 11, which latter is in the form of a mercury switch, and thereby causes energization of the relay circuit, resulting in short-circuiting of the resistance 79 and consequently increased speed of the motor 80. This effects increased circulation of mercury liquid from the drum through the heating tubes and increase in pressure or drop in temperature of the mercury liquid contained in the header 65. A pressure temperature differential responsive device of this kind is more fully described in the Patent No. 2,088,623 to E. S. Thomson, issued August 3, 1937, and assigned to the same assignee as the present application. In the present arrangement this device serves to prevent evaporation of liquid before the liquid has reached a certain point in the fluid circuit, more specifically before the liquid has entered the last up-tubes of the fluid circuit.

While the combustion chamber in Fig. 1 includes down-tubes only, the combustion chamber in Fig. 2 includes both up-tubes and down-tubes, the mercury being heated first in the up-tubes and then in the down-tubes, which latter are connected in series with the up-tubes. The supply tubes 71, 72 have been shown external the furnace to simplify the arrangement somewhat. Ordinarily in a boiler of the kind described it is desirable to place these tubes also inside the combustion space in the form of down-tubes lining the walls of the combustion chamber. Thus, an arrangement according to my invention includes one or several rows of series-connected vertically arranged up and down-tubes lining the walls of a combustion chamber through which mercury is forced by means including a motor-operated pump and from which heated mercury liquid is discharged at the lower end of the down-tubes into the inlets of a plurality of up-tubes located in a convection space and having upper ends connected to a drum.

What I claim as new and desire to secure by Letters Patent of the United States, is:

1. A mercury boiler comprising walls forming a combustion chamber and a convection chamber communicating at their lower ends, vertical down-tubes substantially completely lining the wall in the combustion chamber and vertical up-tubes connected to the lower ends of the down-tubes and lining the wall in the convection chamber, means including a pump for forcing

mercury into the down-tubes, and means including a device responsive to changes of the condition of the mercury near the lower ends of the tubes for controlling the circulation of mercury to prevent evaporation of liquid in the down-tubes.

2. A mercury boiler comprising walls forming a combustion chamber and a convection chamber adjacent the combustion chamber and arranged to receive gases discharged from the latter, a drum located near the convection chamber and above the combustion chamber, vertical down-tubes lining the wall of the combustion chamber, means including a motor-driven pump for forcing liquid from the drum into the upper ends of the down-tubes, vertical up-tubes located in the convection chamber and connected between the lower ends of the down-tubes and the drum, and means including a device responsive to changes of the condition of the mercury near the lower ends of the tubes for controlling the operation of the pump to prevent evaporation of mercury liquid in the combustion chamber.

3. A mercury boiler having walls forming a combustion chamber and a convection chamber adjacent the combustion chamber, the convection chamber having a lower end communicating with the combustion chamber and an upper enlarged portion, a drum located above the combustion chamber and below the enlarged portion of the convection chamber, down-tubes lining the walls of the combustion chamber, up-tubes disposed in the convection chamber and having lower ends connected to the lower ends of the down-tubes, means including a pump for forcing mercury liquid from the drum into the upper ends of the down-tubes, and a bank of inverted convection heating tubes in the enlarged portion connected in series between the upper ends of the up-tubes and the drum.

4. A mercury boiler having combustion and convection heating chambers with rows of down-tubes in the combustion chamber and up-tubes in the convection chamber and connected in series with the down-tubes, means for forcing mercury liquid through the down-tubes, and means including a device responsive to changes of the condition of the mercury near the lower ends of the tubes for controlling the evaporation level of the mercury to prevent evaporation before the mercury liquid has entered the lower ends of the up-tubes.

ARTHUR R. SMITH.
